UNITED STATES PATENT OFFICE.

GEORGE HOLT FRASER, OF NEW YORK, N. Y.

SEPARATOR.

1,165,868.

Specification of Letters Patent. Patented Dec. 28, 1915.

Original application filed December 29, 1910, Serial No. 599,913. Renewed March 30, 1915, Serial No. 18,128. Divided and this application filed June 29, 1915. Serial No. 37,031.

To all whom it may concern:

Be it known that I, GEORGE HOLT FRASER, a citizen of the United States, residing in the borough of Brooklyn, in the county of 5 Kings, in the city and State of New York, United States of America, have invented certain new and useful Improvements in Separators, of which the following is a specification, being a division of my application No. 599,913, filed December 29, 1910.

This invention relates to devices for separating, sizing, bolting, classifying, treating or collecting, materials by utilizing a fluid current, and aims to provide certain 15 improvements therein.

Heretofore it has been common to distribute material within a feed chamber in which air currents act to draw the fine material into an outer casing, the fines settling 20 in the outer casing and the air returning to the feed chamber, the coarse material falling through the air currents in the feed chamber and discharging from the bottom of the latter.

25 My invention provides improvements especially applicable to devices of this general character, and in its preferred form it utilizes a non-rotary feed tube and an initial distributor, in conjunction with a plurality of superposed annular distributers successively receiving the material, an annular exhaust chamber, a blower, an annular discharge passage for the combined exhaust, a centrifugal separator for the dust 30 laden current, and a settling chamber receiving the return current and precipitating the material in suspension therein, a reverse return passage for the settling chamber, means for separately withdrawing the different products, means for adjusting the current, and means for controlling the current.

35 My invention also includes means for independently driving the distributer and blower, means for adjusting the non-rotary feed spout, improved bearing and bearing dispositions, improved damper arrangements, and various features of improvement in construction, arrangement and details, 40 all of which will be hereinafter more fully set forth.

The accompanying drawing which shows

one adaptation of my invention is a vertical axial section showing the preferred form of my invention.

55

Referring to the drawing, A indicates a casing, B the driving mechanism, C the feed hopper, D the distributer, E a feed chamber, X' a blower, G the dust chamber, Y' the return passage, I the coarse outlet, and 60 j the fine outlet. These may be of any usual or suitable construction and arrangement capable of distributing the feed, creating the necessary current, and collecting and discharging the products.

65

Referring to the drawing I will now describe in detail the preferred form of my invention in the adaptation therein illustrated.

The casing A has a cylindrical body a, 70 and tapering or conical top and bottom, made in sections, preferably halves, braced and flanged, and adapted to be bolted to the adjoining circumferential sections, and it has as many vertical sections as are desired 75 to give the requisite height, two being shown. These sections are shown as straight and connected by bars b which tend to preserve the cylindrical form of the body and support the internal parts in position. 80 The upper part of the casing consists of a head c which is tapered in the form of a truncated cone and has an annular top d, and a central cavity or depressed portion e. The lower part of the casing consists of a 85 conical bottom f, suspended from the top body a. The body a is suspended from the top d, and the latter is suspended from the bearing frame g.

The driving mechanism shown consists 90 of a driving shaft h carrying fast and loose pulleys i, and geared to the driven parts by bevel gears. This shaft is mounted in bearings in the frame g, which frame is shown as crossing the machine and supported by 95 timbers at each side thereof, and the entire device as shown is suspended from the frame, which has one face coinciding with the diametric parting of the body.

The hopper C is preferably a stationary 100 hopper, adapted to turn in any direction to connect with any source of feed, and preferably having a scalper and a tailing chute, and a screw threaded discharge outlet.

The feeder is preferably a non-rotary feed pipe *J* which is preferably vertically adjustable, as by screwing into the hopper outlet, and which leads into the casing and 5 discharges onto a distributor *K* therein, the speed of feed being determined by vertical adjustment of the pipe, or of the distributor, or of both, as desired. The distributor is preferably a rotary member, and preferably 10 comprises the disk *K* and one or more successive distributors, as the rings *L* and *M*, which are carried by and revolve with the disk *K* in the construction shown.

Opposite the disk *K* there is located a 15 baffle ring *k* receiving the discharge therefrom and deflecting it downwardly toward the ring *L*, opposite which there is another similar baffle ring *l*, receiving discharge from the ring *L* and directing it down onto 20 the ring *M*, opposite which there is another baffle ring *m* deflecting the material downwardly toward the return cone *O*. Opposite each baffle ring is an annular exhaust passage. These are lettered *P* *Q* and *R* 25 respectively and are surrounded by and discharge into an annular exhaust chamber *T*, which extends downwardly and outwardly and directs their combined discharge into the annular return passage *U*, through which it passes to the dust chamber *G*. As the current descends and escapes 30 from the passage *U* the heavier dust may be close to the outer wall, from which it will slide into the chamber *G*, and the inner 35 air will be correspondingly cleaned. The chamber *G* has a cylindrical discharge pipe *j*. As the air discharges from the passage *U* into the settling chamber *G* the returning air is drawn from it by an annular in- 40 take or upwardly extending return passage *U'*, of greater superficial area than that of the passage *U* and immediately adjacent thereto, so that the downward motion of 45 the dust in the discharge from the passage *U* may have opportunity to throw out much dust centrifugally within the chamber *G* as the air current reverses to reach the return *U'*. The air in the chamber *G* cleans itself by the process of settling, and by 50 momentum and precipitation, before escaping through the return *U'*, the area of which relative to the passage *U* is sufficiently great to so diminish the speed of flow of the return current for the air to 55 largely free itself of floating particles.

An annular suspended wall *w* constitutes the inner wall of the passage *U* and serves as one outer wall of the chamber *G*. The cone *X* constitutes the inner wall of this 60 chamber. In reaching these passages *P* *Q* and *R* the air must traverse the descending shower of material falling from the distributor, composed of coarse and fine material, from which, as the current passes 65 through, particles fine enough to be floated

by it will be carried outward and downward through the blast chamber *T* while the coarser material will continue over the distributor to the return cone *O* and be dropped from the latter into the bottom of 70 the tailings cone *S*.

Adjustment or regulation of the current as to the different distributors may be obtained by differentiating the blower speed, or otherwise, but is preferably affected 75 from within the chamber *E*, as by the damper *Y* controlling the passage *y* beneath the disk *K*, the damper *Z* controlling the passage *z* beneath the distributor *L*, and the damper *A'* controlling the inlet *a'* beneath 80 the distributor *M*.

Inclined annular walls *b'* are preferably attached beneath each distributor, and preferably carry blades *c'* which act as blowers to aid in accelerating the current beneath 85 the distributors.

The dampers *Y*, *Z* and *A'* are independently adjustable from below in any suitable manner, as by the rod *d'* and pipes *e'* and *f'* respectively. 90

When independent speeds of the distributor and the blower are desired the distributors are carried by and driven from a tubular head *B'* which is suitably spaced above them to permit the necessary passage 95 for material between the disk *K* and the head, and which extends upwardly around the pipe *J*, and is adjustably suspended from the bearing *D'*, and is driven through a gear *E'*, which is preferably driven by 100 a cone pulley *F'* and belt *G'* from a reverse cone pulley *H'* on the shaft *h*. By shifting the belt the relative speeds of the pulleys *F'* and *H'* can be regulated.

All bearings consist of an annular cup 105 *i'* receiving an annular flange *j'* so that the bearings run in oil. Each bearing is clamped in a half socket in the frame *g* so that by removing the clamps the parts can be bodily removed sidewise, the parting faces of these clamps correspond with the diametric parting of the casing, so that by removing a detachable half the interior is accessible. 110

The gears, bearings and collars, are enclosed for dust protection, and the upper bearing *D'* is formed on a frame *m'* removably carried on the frame *g* so that, when differential speeds between the distributor and the blower are not desired, this frame 120 may be removed and the bracket *n'*, detachably carrying the feed tube and supporting the hopper, may be lowered onto the bearing *M'* of the frame. In such case the distributors and the blowers may both 125 be carried by the same head.

As thus far described the invention can be used as a current separator alone, but my invention provides for combined mechanical sizings as well as current sizings 130

within the one machine, and this is preferably accomplished by one or more screens beneath the distributing chamber E, receiving the discharge from the return cone O, and grading and sizing it so as to separate out desired sizes before the remaining tailings or fines passing these screens are permitted to fall onto the tailings cone S. Two sizing screens, a coarse inner one Q', and 10 a medium outer one R' each conical and nested together, are shown as yieldingly suspended by springs S' from the return cone O, so as to receive the tailings therefrom. The coarsest material flows down the screen Q' and falls through its outlet to the coarsest outlet q'. Material passing through this screen flows down the screen R' and escapes through the medium outlet r', and material passing through the screen 15 R' flows down the tailings cone S to the tailings outlet I. The outlets r', q' and I are connected to their respective cones by a series of conduits or pipes s' passing each within the next, either concentrically as 20 shown, or nested eccentrically so as to give the greatest external passageway at the lower side if desired. In this manner three mechanical gradings are effected in addition to the current gradings.

25 To agitate the mechanical screens my invention provides a swinging knocker T' which preferably revolves with the distributor and strikes a projection t' on the screen when the latter is depressed, these parts being normally out of coincidence, but being brought into the same path by the depression of the screens either by reason of the weight of material on it if it becomes clogged, or by means of the handle k' when 30 desired. To permit this depression the screens are yieldingly mounted by means of their cylindrical necks l' in the upper ends of their respective pipes s'. Thus they will automatically cause themselves to depress 35 the springs and to be agitated when overloaded, and restore themselves when free from undue weight.

This invention provides an external exhaust and an external blast, which may be 40 used in conjunction with or in substitution for the usual internal blower. I prefer to provide an external return passage U' communicating with the chamber G at the outlet of the passage U and extending upwardly and discharging into a chamber u', which is above and surrounds the feeder, from which a tangential exhaust V' leads 45 to and discharges tangentially into a centrifugal drum v' from which a suction pipe W' leads to an outside fan or outer blower X'. The pipe W' draws downward from an inverted cup or dust apron w' in the drum v'. An annular outlet x' withdraws 50 dust settling in this drum. The chamber 55 u' is an annular exhaust or vacuum chamber

in which the outgoing current is whirled centrifugally to cyclonically equalize it as it is sucked over the apron s affording a contracted annular inlet t from the conduit t''. The blower X' exhausts through the 70 pipe Y' into a blast chamber or equalizing chamber or drum Z' located within the chamber E having a tubular central blast outlet y' therein and an internal equalizing cone z' to insure uniform distribution of the 75 current within the drum.

The current may be increased or regulated by regulating the outside blower X', or by a butterfly or other valve in either its blast or suction pipe, in addition to the 80 regulation which can be obtained by the driving mechanism D or the dampers in the chamber E. C' is such a regulator.

In operation the material entering the feed pipe will be controlled by its adjustment, the speeds and currents will be regulated to give the desired results and the various products will be separately withdrawn according to classification.

It will be understood that the invention 90 is not limited to the particular details of construction, arrangement and combination set forth, as it can be employed in whole or in part according to any modifications.

What I claim is:

1. In separators and the like, a casing, means for distributing material therein, a discharge chamber surrounding said distributing means, a settling chamber, and current generating means outside of said casing, in combination with an annular upwardly leading suction passage surrounding said discharge chamber and communicating with the latter, and a suction pipe connecting the upper part of said passage with the suction side of said generating means, and a blast pipe connecting the blast side of 95 said generating means with the interior of said casing inwardly of said chambers.

2. In separators and the like, a casing, means for distributing material therein, a settling chamber, and a downwardly extending passage surrounding said distributing means and communicating with said chamber, in combination with an upwardly 100 extending passage surrounding said downwardly extending passage, current generating means outside of said casing, a suction pipe connecting the suction side of said generating means with said suction passage 105 above the outlet of said downwardly extending passage, and a blast pipe connecting the blast side of said generating means with the interior of said casing.

3. In separators and the like, a casing, 110 means for distributing material therein, a tailings cone therein, a settling chamber below said cone, a passage surrounding said distributing means and communicating 115 with said settling chamber, an annular ex- 120

115

120

125

130

haust passage above said surrounding passage, a blower outside of said casing, a pipe connecting the said suction side of said blower with said exhaust passage, and a 5 pipe connecting the blast side of said blower with the interior of said casing.

4. In separators and the like, a casing, means for distributing material therein, a tailings cone, a settling chamber, and a 10 chamber surrounding said distributing means and communicating with said settling chamber, in combination with an annular exhaust chamber above said settling chamber and having a tangential outlet, a 15 blower outside of said casing, a suction pipe connecting said outlet with said blower, and a blast pipe communicating from said blower to the interior of said casing.

20 5. In separators and the like, a casing having a suction outlet and a blast inlet, means for distributing material therein, means for causing a fluid current to traverse such material therein, and a blower outside 25 of said casing, in combination with a suction pipe communicating between said blower and said suction outlet, and comprising a circular drum, a tube leading from said casing and discharging tangentially into said drum, an inverted cup-shaped 30 member open at bottom and closed at top, and depending within said drum, and an open ended vertical pipe disposed concentrically within said member and connected to the suction side of said blower, and a blast pipe connecting the blast side 35 of said blower with said blast inlet.

6. In separators and the like, a casing, means for distributing material therein, a 40 tailings cone, a settling chamber, a tailings pipe leading from said cone and affording a downward conduit for tailings, a current discharge pipe, and a blower outside of said casing having its suction connected to said 45 discharge pipe, in combination with a blast pipe connected to said blower and within and extending longitudinally of said tailings pipe and communicating with the interior of said cone.

50 7. In separators and similar devices, a casing, a plurality of distributor therein for material to be separated, means comprising an independent outwardly extending exhaust passage opposite each distributor, an 55 annular exhaust chamber surrounding said distributor, and an open bottom tailings receptacle below said distributor, in combination with a blower outside of said casing having its suction connected to said exhaust 60 chamber, and a blast pipe connecting the blast side of said blower with the interior of said casing and discharging upwardly through the bottom of said receptacle.

65 8. In separators and similar devices, a casing, a distributor therein for material to

be separated, and a blower, in combination with an annular downwardly extending exhaust passage surrounding said distributor, an annular upwardly extending return passage outwardly of and surrounding said exhaust passage, and a settling chamber below and communicating with said passages. 70

9. In separators and the like, a casing, a distributor for material therein, means for causing a current to flow therein, and a discharge chamber surrounding said distributor, in combination with an annular upwardly extending current passage above said chamber, an annular outlet chamber surrounding said passage, an upwardly projecting circular open topped partition in said outlet chamber surrounding said passage and affording an annular outlet therefrom to said outlet chamber. 75 80

10. In separators and similar devices, a 85 casing having a feed inlet, a distributor for material therein, and means causing a current to traverse material falling from said distributor, in combination with a discharge chamber surrounding said distributor and having an outer annular outlet, an annular inwardly and upwardly tapering wall above said chamber affording a current passage above said chamber communicating with said outlet and surrounding said inlet, a 90 blower, a suction pipe connecting the upper part of said current passage with said blower, and a blast pipe connecting said blower with the interior of said casing. 95

11. In separators and similar devices, a 100 casing having a central feed inlet and means for causing a current to traverse material fed into said casing, in combination with means for feeding material thereto, an exhaust for such current comprising an annular outlet surrounding said inlet and having an outlet passage at one extremity leading outside of said casing, a blower, a pipe leading from said passage to the suction side of said blower, and a blast pipe leading from 105 said blower to the interior of said casing. 110

12. In separators and similar devices, a 115 casing, means for feeding material thereto, and means for causing a current to traverse material fed into said casing, in combination with means for delivering a current in said casing comprising a blast chamber having a central opening in its top, an annular wall within and partitioning said chamber, closed at its bottom and open at its top and 120 affording an annular inwardly extending outlet passage between its top edge and the top of said chamber, and a blower connected at its blast side to said chamber.

13. In separators and the like, a casing, 125 means for distributing material in an annular descending blanket therein, and means for causing a current to flow outwardly through such material, in combination with an annular outer relatively low pressure 130

discharge chamber in said casing surrounding said distributor, an annular outer collecting chamber in said casing below and communicating with said discharge chamber, a central relatively high pressure chamber below and inwardly of said distributing means, a blower outside of said casing, and means for effecting relatively low and high pressure differences in said outer and inner chambers respectively comprising a closed passage connecting the suction and blast sides of said blower with the outer and inner chambers of said casing respectively.

14. In separators and the like, a casing, means for distributing material therein, and means for causing a current to flow outwardly through such material, in combination with means affording an upwardly discharging return passage for such current below and inwardly of said distributing means, and a plurality of annular walls inwardly of said distributing means in the path of the returning current for subdividing such current into isolated strata before flowing outwardly through such material.

15. In separators and the like, a casing, means for causing material to descend in an annular stream therein, and means for causing a current to flow outwardly through such material, in combination with spaced annular means within said casing for dividing such current into superposed outwardly flowing strata, an upwardly discharging current pipe inwardly of said annular means, and a blower connected to said pipe and casing.

16. In separators and the like, a casing, means for feeding material thereto, a plurality of superposed annular distributors therein for causing such material to descend in an annular wall or blanket within said casing, and an annular discharge chamber surrounding said distributors, in combination with a tailings cone below said distributors, a blower outside of said casing having a suction pipe communicating with said discharge chamber at the outer side of said annular distributors, and a blast pipe communicating upwardly through said tailings

cone with the interior of said casing at the 50 inner side of said distributors.

17. In separators and the like, a distributor, means for causing a current to traverse material distributed therefrom to remove floating material therein, annular 55 screening means spaced apart from said distributor to afford a current passage beneath the latter receiving remaining material, and means affording a fluid conduit communicating with said passage and discharging 60 inwardly of said screening means for returning such current within the latter.

18. In separators and similar devices, the combination with a casing, means for distributing material therein, a screen in said 65 casing receiving such material and spaced apart from said distributor to afford a fluid passage above said screen, separate outlets for coarse and fine from said screen, means outside of said casing communicating with 70 said passage for causing a fluid current to traverse the latter, and means for returning such current to said casing.

19. In combination, means causing a current to traverse material to be screened, a 75 circular screen receiving such material, means affording a passage for a fluid current to traverse such material above said screen, a blower communicating with said passage, and a return pipe from said blower 80 extending within and discharging inwardly of said screen.

20. In combination, a casing, a revolving distributor therein, a conical screen spaced apart from said distributor to afford a current passage beneath the latter and having a bottom discharge opening, a blower outside of said casing having its suction connected with said passage and its exhaust communicating with said opening, and means for jar- 85 ring said screen.

In witness whereof, I have hereunto signed my name in the presence of two subscribing witnesses.

GEORGE HOLT FRASER.
